T. S. CASNER

RELAY

Filed March 24, 1921

UNITED STATES PATENT OFFICE.

THADDEUS STEPHENS CASNER, OF PLAINFIELD, NEW JERSEY, ASSIGNOR, BY MESNE ASSIGNMENTS, TO RADIO ELECTRIC CLOCK CORPORATION, OF NEW YORK, N. Y., A CORPORATION OF DELAWARE.

RELAY.

Application filed March 24, 1921. Serial No. 455,261.

20 all whom it may concern:

Be it known that I, THADDEUS STEPHENS CASNER, a citizen of the United States, and residing at Plainfield, Union County, State of New Jersey, have invented certain new and useful Improvements in Relays, of which the following is a specification.

The present invention relates to electrical relays and particularly to relays to be used in connection with wireless telegraph receiving sets, to receive the electrical impulses from the receiving apparatus, and to open and close a local circuit. The electrical impulses received by the average wireless telegraph receiving apparatus are relatively weak and the electrical impulses sent to the receiver of the apparatus are also weak though greatly amplified, being only faintly audible. In certain types of mechanism it is highly desirable to have a relay by means of which a local circuit can be opened and closed in accordance with the wireless signals sent from a distant transmitting station, for instance at Arlington, Va. In my copending application Serial 455,262 dated March 24, 1921, is disclosed a mechanism for automatically setting the hands of a clock in accordance with such wireless signals received each day at noon. This involves an electro-mechanical mechanism for adjusting the clock hands, a wireless receiving set, and a relay operatively connecting the two sets of apparatus. The relay herein disclosed is particularly applicable for use in such combination but is not limited in this respect being of general application and capable of being used in all cases where it is desired to use a relay which becomes operative upon receipt of a very faint current impulse.

40 One embodiment of the invention is illustrated in the accompanying drawings, in which,

Figure 1 is a side elevation of the relay, part being broken away;

45 Figure 2 is a front view of the same;

Figures 3 and 4 are perspective views of the two lever arms respectively of the relay, and

50 Figure 5 is a schematic view of the relay and showing a local circuit.

A support or base of insulating material is indicated at 10 in the drawings and mounted on this base member is a bracket which carries the ear piece or receiver 11

and the several parts of the relay mechanism. 55 This bracket has a vertical portion 12 which joins, at its upper end, a short horizontal portion 13 and to the outer end of this horizontal portion is joined a second relatively short downwardly extending portion 14. 60 The bracket is preferably of sheet metal bent into the shape illustrated, but it may be formed in various ways. The vertical portion 12 has its central portion cut away as at 15 and this slot is continued into the horizontal portion 13, as shown in Fig. 1. The base of the bracket has a short upwardly projecting flange 16 provided with a circular aperture into which is inserted an insulating bushing 17. A contact screw 18 has 70 threaded engagement with a cylindrical aperture which extends through this bushing. The telephone receiver 11 is of well-known type, for instance of the type known as the Brandes receiver. The vibratory diaphragm 19 is provided with an integral projection or boss 20 which extends forwardly and has its outer end in contact with the lever 21 at the middle point thereof, which lies parallel to the diaphragm 19. This 75 lever is rotatably mounted on knife edges 22 of plate 23 which is secured to the rim of the receiver. Extending through this plate is an adjusting screw 24 having threaded engagement with a sleeve 25 to which is 80 rigidly secured the flat spring 26. One end of this spring bears against plate 23 and its other end bears against the lower end of lever 21 and normally tends to keep this lever pressed against boss 20. 85

A soft rubber sleeve or covering 27 is provided for the free end of lever 21 and resting against this rubber covering is one end of a screw 28 which has threaded engagement with a second lever 29 arranged 95 parallel to the first lever and rotatably mounted at its upper end on knife edge 30. A spring 31 normally tends to maintain the lower end of this lever pressed toward the receiver with the head of screw 28 engaging 100 the rubber covering of the free end of lever 21. A screw 32 is provided for adjusting the pressure of spring 31 against lever 29. Screw 28 is located at approximately one-fourth of the distance between knife edge 30 105 and the lower end of lever 29. Contact screw 18 has its point normally in contact with the lower end of lever 29. Lever 29 is

in electrical circuit with the battery 33 and an electro-magnet 34 which electro-magnet, being normally energized, normally maintains an armature 35, in a second circuit, out 5 of contact with an adjustable contact 36 so that this second circuit is normally open. A spring 37 normally tends to close the circuit against the action of electro-magnet 34 and if this magnet is de-energized the spring 10 will immediately move the armature to the right (Fig. 5) and close the secondary circuit.

When impulses are received from a wireless receiving set by the receiver the diaphragm 19 vibrates very rapidly, and this rapid movement is transmitted to lever 21 which is spring pressed against the boss 20 projecting from the diaphragm. Adjusting screw 28 of lever 29 at all times 20 tends to remain in contact with the rubber covering on the end of lever 21 and is struck a great many light blows thereby, as the diaphragm vibrates. The diaphragm, as it vibrates, also tends to move 25 toward the left (Fig. 1) and the lever 29 will move toward the left and open the circuit through electro-magnet 34. The movement of the lower end of lever 29 is of course eight times greater than the movement of the boss 14 on the diaphragm because of the multiplying effect of the levers.

Lever 29 is made longer and heavier than lever 21 and, due to the soft cushion 27, and its own weight, it cannot respond to 35 individual vibrations, but only to a series of vibrations. Thus when the diaphragm 19 vibrates, the lever 21 and cushion 27 vibrate and lever 29 tends to follow the vibration of lever 21 but cannot do so due 40 to its weight and length. In vibrating the diaphragm 19 also shifts its center of vibration slightly toward the left (in the Brandes receiver) and levers 21 and 29 follow it, thus opening the local circuit at contact 18. 45 The rubber cushion acts to prevent chattering of the relay levers and to prevent lever

29 from bouncing away from lever 21. It gives a smooth action to the relay and insures the proper opening and closing of the local circuit.

The design and arrangement of the component parts of the invention may be varied without departing from the spirit and scope of the invention.

What is claimed is:

1. In a relay of the class described, in combination, a vibratory diaphragm, a lever parallel to said diaphragm said lever being pivoted at one end and operatively connected at its middle point to the center of the diaphragm, a second lever parallel to the first lever pivoted at one end and operatively connected at its quarter point to the free end of the second lever, spring means normally tending to move both of said levers toward the diaphragm, and an adjustable stop limiting the outward movement of the second lever, said stop constituting the fixed contact of a switch and said second lever constituting the movable contact.

2. In a relay of the class described, in combination, a vibratory diaphragm, a lever pivotally supported adjacent said diaphragm and operatively connected thereto, a second lever pivotally supported adjacent said first lever and operatively connected thereto, and a separate spring for each of said levers normally urging the same toward the diaphragm.

3. In a relay of the class described, in combination, a vibratory member, and means for multiplying the movements of said member including a lever, means normally pressing said lever into operative engagement with the vibratory member, a second lever, means normally pressing said second lever into engagement with the first lever and a cushion between said levers and holding them apart.

In testimony whereof I hereunto affix my signature.

THADDEUS STEPHENS CASNER.
